UNITED STATES PATENT OFFICE.

WAYNE K. BEYERL, OF SCHENECTADY, NEW YORK, ASSIGNOR TO GENERAL ELECTRIC COMPANY, A CORPORATION OF NEW YORK.

SWITCH MECHANISM.

Application filed May 20, 1921. Serial No. 471,086.

To all whom it may concern:

Be it known that I, WAYNE K. BEYERL, a citizen of the United States, residing at Schenectady, county of Schenectady, State of New York, have invented certain new and useful Improvements in Switch Mechanism, of which the following is a specification.

My invention relates to automatic circuit controlling devices and an object is to provide improved means for resetting the tripping mechanism of such devices, whereby the resetting is automatically performed concurrently with the operation of the circuit controlling device so that no thought or care on the part of the operator is required to insure proper operation.

Another object of my invention is to provide means for resetting the tripping mechanism early in the switch closing operation, arranged to operate without shocks to the tripping mechanism and arranged to maintain the tripping mechanism in the reset position up to the final closing movement of the switch contacts, whereby the maximum time for abnormal circuit conditions to clear themselves is insured without making it possible for the operator to hold the switch closed if abnormal conditions still prevail.

A further object of my invention is to provide a switch operating mechanism which shall be sturdy in construction and reliable in operation and which shall enable the switch to be opened or closed by a simple operation of the switch operating means and which shall permit the circuit to be automatically opened independently of the operating lever when abnormal conditions exist on the circuit.

My invention will be better understood from the following description taken in connection with the accompanying drawings and its scope will be pointed out in the appended claims.

Figure 1 is an elevation of an embodiment of my invention, the parts being shown in switch closed position; Fig. 2 is an elevation of the embodiment of my invention shown in Fig. 1, the parts being shown in switch opened position; Fig. 3 is an elevation of a modification of my invention, the parts being shown in switch closed position; Fig. 4 is an elevation of the form of my invention shown in Fig. 3, the parts being in switch opened position; Fig. 5 is a perspective of the modification of my invention shown in

Fig. 3 with parts broken away, and Fig. 6 is an elevation of the modification of my invention shown in Fig. 3 showing the switch operating lever near the end of its closing movement.

In the embodiment of my invention shown in Figs. 1 and 2, there is mounted in a suitable casing or box 1 of a switch, a switch operating mechanism 2 arranged to be controlled in response to predetermined circuit conditions by an electroresponsive device 3.

The switch operating mechanism 2 comprises a shaft 4, mounted to turn on which, is a switch lever 5 having pivotally connected thereto a switch rod 6 that carries suitable contact controlling members 6' for example. The switch lever 5 is biased by a spring 7 to turn clockwise on the shaft 4, that is in a direction to cause the opening of the switch contacts. Also on the shaft 4, is a pivotally mounted member 8, hereinafter called an intermediate lever for clearness in description, biased to turn in a clockwise direction by a spring 9 and connected to the switch lever 5 by a collapsible connection or toggle comprising links 10 and 11 which are pivotally connected at 12, the link 10 being pivoted to the intermediate lever 8 at 13 and the link 11 to the switch lever 5 at 14. The toggle formed by links 10 and 11, when straightened and latched by a catch lever 15 which engages the link 10 at its end 16, locks the switch lever 5 and the intermediate lever 8 so that they are rotatable as a unit on the shaft 4 in a counter-clockwise direction, that is in a direction to close the switch contacts. The catch lever 15 is pivoted to the link 11 at a point intermediate its ends. When the toggle is latched, the switch lever 5 and the intermediate lever 8 are rotatable on the shaft 4 by an operating lever 17 secured to the shaft 4 to rotate therewith and turn the dog 18 which is also secured to the shaft 4 to rotate therewith, the dog 18 having a projecting portion 19 arranged to bear against the intermediate lever 8. Pivoted on a shaft 20, that is mounted in the casing 1, is a resetting lever 21, biased to turn in a clockwise direction by a spring 22 and provided with a roller 23, adapted to move along the cam-shaped edge 24 of the intermediate lever 8 and normally seated in a concave portion 25 of said edge to prevent the intermediate lever from moving under the action of spring 110

9 to straighten the toggle links 10 and 11 until it is desired to reset the switch after it has been opened by the electroresponsive device 3 which may be responsive to underload, under voltage or other predetermined conditions on the circuit controlled by the switch.

The electroresponsive device 3 comprises a frame 26 secured to the casing 1 and supporting a coil 27 having a core 28 and adapted to be connected in circuit with the line protected by the switch. Pivotally mounted on the frame 26 is an armature 29 biased to turn in a counter-clockwise direction by a spring 30 and also by gravity and provided with a tripping lug 31 arranged to engage the trip lever 15 and a resetting lug 32 adapted for engagement with the projecting portion 33 of the resetting lever 21. The armature 29 may be provided with a short circuited coil 34 to prevent chattering when the switch is used on alternating current circuits.

The operation of the embodiment of my invention shown in Figs. 1 and 2 is as follows: Assuming, as shown in Fig. 1, that the parts are in the switch closed position, underload, undervoltage or other predetermined conditions to which the electroresponsive device 3 is responsive, will cause the core 28 to release the armature 29 which under the action of spring 30 and gravity, turns in a direction to cause the tripping lug 31 to hit the catch lever 15 thereby releasing the toggle link 10 and allowing the toggle to buckle. The switch lever 5 is then free to move on the shaft 4 independently of the intermediate lever 8 and, under the action of the spring 7 assisted by the weight of the switch parts, moves in a direction to cause the switch rod 6 to open the switch contacts. The various parts are then in the switch opened position as shown in Fig. 2, the projecting end 35 of the switch lever 5 coming against shaft 20 as a stop to arrest its motion.

To close the switch, the operating lever 17 is first turned clockwise thus turning the shaft 4 and the dog 18 secured thereto, until a lug 36 on the dog 18 comes into contact with the corner 37 of the resetting lever 21 and turns this lever sufficiently to raise the roller 23 out of the concave portion 25 of the intermediate lever 8 thereby releasing the lever 8 which under the action of the spring 9 at once turns in a clockwise direction to straighten the toggle and thus lock the intermediate lever 8 and the switch lever 5 for the switch closing movement. As the resetting lever 21 is turned by the lug 36 of the dog 18, the projecting portion 33 bears against the resetting lug 32 on the armature 29 and turns the armature 29 to the position it occupies when attracted by the coil 28. The clockwise movement of the

operating lever 17 is finally arrested by a projecting portion 38 of the lug 36 which comes to a stop against shaft 20. When the intermediate lever 8 moves to straighten the toggle, the roller 23 rides upon the cam-shaped edge 24 and the resetting lever 21 is thus maintained in a position to hold the armature 29 against its core 28, until such time as the roller 23 is again enabled to seat in the concave portion 25 of the cam-shaped edge 24. The operating lever 17 is now turned counter-clockwise and the projection portion 19 on the lug 18 bears against the intermediate lever 8 thus turning it and the switch lever 5 locked thereto by the latched toggle links 10 and 11 in a direction to cause the rod 6 to close the switch contacts. As the lever 17 is moved, the roller 23 on the resetting lever 21 follows along the cam-shaped edge 24 until it rides over the upper convex portion thereof and drops into the concave portion 25 with the final movement of the operating lever, thus releasing or freeing the resetting lever 21 from the resetting lug 32 of the armature so that if the coil 27 is not sufficiently energized the armature 29 is free to drop and trip out the switch as heretofore described, but if the coil 27 is sufficiently energized to hold the armature in the attracted position against the action of spring 30 and gravity, the switch will remain closed. The switch may be opened, whenever desired, without buckling the toggle by turning the operating lever 17 and therefore the dog 18 clockwise, until the lug 36 on the dog 18 turns the resetting lever 21 sufficiently to raise the roller 23 out of the concave portion 25 of the cam-shaped edge 24. The switch lever 5 and the intermediate lever 8 under the joint action of springs 7 and 9 assisted by the weight of the switch parts, then turn clockwise as a unit on the shaft 4 to open the switch.

In the modification of my invention shown in Figs. 3, 4, 5 and 6, there is mounted in a suitable switch casing or box-like structure 39, a switch operating mechanism 40 arranged to be tripped by a suitable electroresponsive device 41.

The switch operating mechanism comprises a switch lever 42 mounted to turn on a shaft 43 and move thereby suitable contact controlling members, not shown, which are connected thereto. The switch lever 42 is biased to turn in switch opening direction by a spring 44. Also on the shaft 43, is a pivotally mounted member 45, hereinafter called an intermediate lever for clearness in description, that is connected by links 46 to an operating lever 47 mounted to turn on a shaft 48. The intermediate lever 45 is connected with an arm 49 of the switch lever 42 by a collapsible connection or underset toggle comprising links 50 and 51 which are pivotally connected by a pin 52, the link 50

being pivoted to the intermediate lever 45 at 53 and the link 51 to the switch lever arm 49 at 54. The link 51 is provided with a stop 55 which seats on the link 50 to prevent 5 overtravel of the toggle when straightened. The toggle formed by the links 50 and 51, when straightened and latched by a catch lever 56, pivotally mounted on the link 51 and arranged to engage the link 50 at one 10 end thereof, locks the switch lever 42 and the intermediate lever 45 so that they are rotatable as a unit on the shaft 43 by the operating lever 47 in a counter-clockwise direction, that is in the direction to close the 15 switch contacts.

The electroresponsive device 41 comprises a frame 57 on which is mounted a coil 58 provided with a suitable magnetic structure 59. The coil 58 is adapted to be connected 20 in circuit to control the operation of an armature 60, pivotally mounted on the frame 57, in response to predetermined conditions, for example, underload, under-voltage, etc., on the circuit protected by the 25 switch. The armature 60 may be provided with a short circuited coil 60' to prevent chattering when the device is used on alternating current circuits. The armature 60 is connected by a link 61, see Fig. 5, to 30 a trip lever 62, pivotally mounted on the frame 57 and biased by a spring 63 to assist gravity in turning the armature 60 from its attracted position when the magnetic effect of coil 58 is not sufficient to hold 35 it. The catch lever 56 is provided with a trip lug or projection 64 arranged to be engaged by a projection or lug 65 on the trip lever 62, thus releasing the catch lever 56 from the link 50 to allow the toggle to 40 buckle. Pivotally mounted on the frame 57 is a resetting lever 66, as best shown in Fig. 5, biased by a spring 67 to turn to a position such that a resetting lug 68 on one end thereof bears on the trip lever 62 45 to turn the armature 60 into the position it occupies when attracted by the coil 58. The other end of the resetting lever 66 is provided with a releasing lug 69 against which the lower end 70 of the intermediate 50 lever 45 is adapted to bear so as to turn the resetting lever 66 into a position such that the resetting lug 68 is clear of the trip lever 62 thereby freeing the armature 60 so that it can move from its attracted position if 55 the coil 58 is not sufficiently energized.

The operation of the embodiment of my invention shown in Figs. 3, 4, 5 and 6 is as follows:—Assuming, as shown in Fig. 3, that the parts are in the switch closed position, the occurrence of a predetermined condition on the circuit controlled by the switch will cause the electroresponsive device 41 to release the armature 60. The weight of the armature 60 combined with the action of the spring 63 turns the trip

lever 62 in a direction to cause its lug 65 to hit the trip lug 64 on the catch lever 56 thereby releasing the toggle link 50 and allowing the toggle to buckle. The switch lever 42 is then free to move on the shaft 70 43 independently of the intermediate lever 45 and, under the action of the spring 44 assisted by the weight of the switch parts, turns in a clockwise direction to cause the 75 opening of the switch. The various parts are then in the switch opened position, as shown in Fig. 4.

To close the switch, the operating lever 47 is first turned clockwise thus turning the intermediate lever 45 clockwise. The resetting lever 66 also turns clockwise under the action of the spring 67, the releasing lug 69 thereof bearing against the lower end 70 of the intermediate lever 45. The intermediate lever 45 normally, that is to say, when the operating lever 47 is in the closed position, see Figs. 3 and 4, bears against the releasing lug 69 to hold the resetting lever in a position such that the resetting lug 68 is clear of the trip lever 62. 80 When the operating lever 47 has been turned sufficiently, the resetting lug 68 on the resetting lever 66 bears against the trip lever 62, see Figs. 5 and 6, which, under the action of the spring 67, is caused to raise the armature 60 into the position it occupies when attracted by the coil 58. Further clockwise movement of the operating lever 47 straightens the toggle which is locked by the catch lever 56 engaging the link 50, thus locking the switch lever 42 and the intermediate lever 45 to turn as a unit on the shaft 43. The various parts are now in position for the switch closing movement which is accomplished by turning the operating lever 100 in a counter-clockwise direction. This movement of the operating lever 47 causes the switch lever 42 and the intermediate lever 45 to move as a unit on the shaft 43 and just prior to the final closing movement of the switch lever 42, see Figs. 5 and 6, the lower end 70 of the intermediate lever 45, engages the releasing lug 69 of the resetting lever 66 which is thus turned counter-clockwise so as to raise the resetting lug 68 clear of the trip lever 62. Therefore, if predetermined conditions to which the electroresponsive device 41 is responsive prevail on the circuit controlled by the switch, the armature 60 will be free to turn from its reset or attracted position to cause the tripping of the catch lever 56 and thereby the opening of the switch independently of the operating lever 47 as heretofore explained. If, however, the armature 60 remains in the reset or attracted position, the overset toggle, formed by the link 46 and the upper end of the operating lever 47, holds the parts in the switch closed position but 110 free to operate to open the switch upon 115 120 125 130

the occurrence of predetermined conditions to which the electroresponsive device 41 is responsive. The part of the operating lever 47 pivoted to the link 46 operates through a slot in the casing 39 and the lug 47' which engages the casing 39 to prevent overtravel of the toggle also closes the slot in the casing to exclude dust or other foreign materials.

10 It is obvious that the switch may be opened whenever desired, without first buckling the toggle formed by links 50 and 51, by turning the operating lever 47 clockwise, thus causing the switch lever 42 and the intermediate lever 45 to turn clockwise as a unit on the shaft 43.

It is, therefore, clear that with switches constructed in accordance with my invention no care or thought need be given to the resetting mechanism during the operation of the switch. It will also be apparent to those skilled in the art that the feature of delayed release of the resetting mechanism allows a maximum possible time for a short circuit or other abnormal condition on the line to clear itself. That is to say, while the switch cannot be held closed with a short circuit or other abnormal condition on the line, it will nevertheless remain closed if the short circuit or other abnormal condition clears itself during the time that the operating lever is being operated to close the circuit. Furthermore, all of the mechanism is enclosed in a dust proof casing and, in the automatic opening of the switch no parts exterior to the switch casing move, thus eliminating any possible danger to attendants or others from levers, etc. moving at unexpected times.

40 Although I have shown and described my invention in considerable detail, I do not wish to be limited to the specific details thereof, as shown and described, but may use such modifications, substitutions or equivalents thereof, as are embraced within the scope of my invention.

What I claim as new and desire to secure by Letters Patent of the United States, is,—

1. An electric switch comprising a rotatably mounted switch lever, a pivotally mounted member, a toggle for locking said switch lever and said pivotally mounted member to turn as a unit, means comprising an armature arranged to be released to trip said toggle to open the switch upon predetermined conditions and an operating lever adapted to be moved in one direction to straighten said toggle and reset said armature and in the opposite direction to close the switch and free said armature in the final closing movement.

2. An electric switch comprising a rotatably mounted switch lever, a pivotally mounted member, a toggle for locking said switch lever and said pivotally mounted

member to turn as a unit, means comprising an armature arranged to be released to trip said toggle to open the switch upon predetermined conditions, means for resetting said armature, and an operating lever adapted to be moved in one direction to straighten said toggle and actuate said resetting means and in the opposite direction to close the switch and in the final closing movement to cause said resetting means to free said armature.

3. An electric switch comprising a shaft, a switch lever mounted to turn thereon, a pivotally mounted member adapted to turn independently of said switch lever, a toggle for locking said switch lever and said pivotally mounted member to turn together, electro-magnetic means comprising an armature arranged to be released to trip said toggle to open the switch in response to predetermined conditions, an operating lever adapted to be moved in one direction to straighten said toggle or open the switch if the toggle has not been tripped and in the opposite direction to close the switch, and means cooperating with said operating lever to reset said armature on the movement of the operating lever in a direction to straighten the toggle and to free said armature on the final movement of the operating lever in a direction to close the switch.

4. An electric switch comprising a pivotally mounted switch lever biased to move in circuit opening direction and provided with a projecting arm, a pivotally mounted member, a collapsible connection between said projecting arm and said pivotally mounted member adapted to be set to cause said pivotally mounted member and said switch lever to turn as a unit, electroresponsive means comprising an armature biased to buckle said collapsible connection to cause the opening of the switch in response to predetermined conditions, a resetting lever biased to reset said armature and arranged to be restrained by said pivotally mounted member, and an operating lever movable in one direction to turn said pivotally mounted member to reset said collapsible connection and release said lever and in the opposite direction to close the switch and move said resetting lever to free said armature.

5. An electric switch comprising a rotatably mounted switch lever biased to move in circuit opening direction and provided with a projecting arm, a pivotally mounted member, a collapsible connection between said pivotally mounted member and said projecting arm adapted to be set to cause said pivotally mounted member and said switch lever to turn together, electroresponsive means comprising an armature adapted to be released in response to predetermined conditions, a trip lever connected to said armature and arranged to buckle said collapsible connection to cause the opening of the switch in response to predetermined conditions.

ble connection, a resetting lever biased to cause said trip lever to reset said armature and normally restrained by said pivotally mounted member, an operating lever connected to said pivotally mounted member and movable in one direction to cause the same to set said collapsible connection and release said resetting lever and in the oppo-

site direction to close the switch, and in the final closing movement to restrain said resetting lever whereby said trip lever is free to buckle said collapsible connection. 10

In witness whereof, I have hereunto set my hand this 19th day of May, 1921.

WAYNE K. BEYERL.
